Fig. 1

Fig. 2

FIG. 1 is a perspective view of a mobile showing my new design, the flag pole portion being broken away for convenience of illustration; and

FIG. 2 is a top plan view thereof when laid out flat, the side opposite that shown being a mirror image thereof.

The side opposite that shown in FIGS. 1 and 2 is symmetrical.

I claim:

The ornamental design for a mobile, substantially as shown and described.
